(57) **CLAIM**

The ornamental design for a temperature probe dock, as shown and described.

DESCRIPTION

FIG. 1 is a perspective view of a temperature probe dock in a closed configuration showing the new design;

FIG. 2 is a perspective view of the temperature probe dock in an open configuration;

FIG. 3 is a left side elevational view thereof in the closed configuration;

FIG. 4 is a left side elevational view thereof in the open configuration;

FIG. 5 is a right side elevational view thereof in the closed configuration;

FIG. 6 is a right side elevational view thereof in the open configuration;

FIG. 7 is a rear elevational view thereof in the closed configuration;

FIG. 8 is a rear elevational view thereof in the open configuration;

FIG. 9 is a front elevational view thereof in the closed configuration;

FIG. 10 is a front elevational view thereof in the open configuration;

FIG. 11 is a top plan view thereof in the closed configuration;

FIG. 12 is a top plan view thereof in the open configuration;

FIG. 13 is a bottom plan view thereof in the closed configuration; and,

FIG. 14 is a bottom plan view thereof in the open configuration.

The broken lines illustrate environment or portions of the temperature probe dock that form no part of the claimed design.

1 Claim, 4 Drawing Sheets
